US00D619178S

(12) **United States Design Patent**
Ashida et al.

(10) **Patent No.:** US D619,178 S
(45) **Date of Patent:** ** Jul. 6, 2010

(54) **CONTROLLER COVER**

(75) Inventors: **Kenichiro Ashida**, Kyoto (JP); **Junji Takamoto**, Kyoto (JP); **Noboru Wakitani**, Kyoto (JP); **Masato Ibuki**, Kyoto (JP)

(73) Assignee: **Nintendo Co., Ltd.**, Kyoto (JP)

(**) Term: **14 Years**

(21) Appl. No.: **29/293,947**

(22) Filed: **Dec. 19, 2007**

(30) **Foreign Application Priority Data**

Jun. 22, 2007 (JP) 2007-016642
Jun. 22, 2007 (JP) 2007-016643

(57) **CLAIM**

The ornamental design for a controller cover, as shown and described.

DESCRIPTION

FIG. 1 is a front, top and left perspective view of a controller cover showing our new design;

FIG. 2 is a rear, bottom and right perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof, a left side view being a mirror image thereof; and,

FIG. 8 is a reference view showing a state where the controller cover is attached onto a controller.

The subject matter shown in broken lines in FIGS. 1-3 and 8 forms no part of the claimed design.

1 Claim, 3 Drawing Sheets
